UNITED STATES PATENT OFFICE.

HARRY BRADLEY ROWAN, OF NORTH ATTLEBORO, MASSACHUSETTS, ~~INVENTOR~~ TO
WHITING & DAVIS COMPANY, A CORPORATION OF NEW YORK.

HANDBAG.

1,354,579.

Specification of Letters Patent.

Patented Oct. 5, 1920.

Application filed April 14, 1920. Serial No. 373,688.

To all whom it may concern:

Be it known that I, HARRY BRADLEY ROWAN, a citizen of the United States, residing at North Attleboro, in the county of 5 Bristol, State of Massachusetts, have invented certain new and useful Improvements in Handbags; and I do hereby declare the following to be a full, clear, and exact description of the invention, such as will 10 enable others skilled in the art to which it appertains to make and use the same.

This invention relates to hand bags or mesh bags of the type used by ladies to carry money, tickets and small articles and consists 15 essentially in a new and improved method of attaching the flexible handle, which is usually made of woven wire, to the frame work of the bag.

It has heretofore been proposed to fasten 20 the flexible handle to the bag by inserting it in a socket element which is rigidly attached to a bail, which in turn is rigidly attached to the frame work of the bag. Any swinging of the bag with relation to 25 its handle is, with such a construction, taken up by the bending of the handle itself inasmuch as the other parts are quite rigid. The continual repetition of this bending as 30 the bag is swung during walking and during the ordinary use of the bag, causes a pronounced weakening, with the possibility of breakage of the flexible handle near the point where it is attached to the bag.

It has also been proposed to pivot the 35 socket, in which the handle is inserted, to the bail, the bail in this instance also being rigidly attached to one of the frame members of the bag. Such a construction remedies this difficulty to a certain extent, but 40 it still presents a number of mechanical difficulties which are overcome by my improved construction. With this proposed construction, that is where the flexible handle is mounted in a socket pivoted to a rigid 45 bail, the top of the bail must necessarily be straight and horizontal in order to provide a suitable mounting for the hinge or pivotal axis of the pivoted socket. This necessity results in an undesirable limitation in 50 the design of the bail, which is of great importance in an art where it is so necessary to please the eye of the feminine user.

My improved construction contemplates the provision of a pivoted bail, in place of

the former rigid bail, whereby the continual 55 swinging of the bag is taken up by the swinging of the bail about its pivot. With the bail pivoted it is then possible to attach the socket in which the flexible handle is mounted rigidly to the bail, which is a distinctly 60 cheaper and sturdier construction than the former one where the socket not only served to mount the handle, but also had to have a hinge at its lower edge to take up the swinging movement. The socket 65 in which the handle is mounted is usually of sheet metal, and is not at all adapted, due to its light weight, to the formation of a hinge along its lower edge. The use of a pivoted bail is of advantage in that it puts 70 all of the pivoting strain on the bail itself, rather than on the lighter handle-carrying socket. This gives a wider and stronger bearing, both because it would be impracticable to make the handle-carrying socket 75 as wide as is possible with my bail, or to make it of as heavy metal as the bail because either of these changes would spoil the proportions and neat appearance of the bag.

The pivotal axis of the pivoted bail, is, in my improved construction, positioned a little way below the ball catch or other fastening element that may be used to hold the two parts of the frame work together, so 85 that the fastening device is positioned in the space formed by the side members of the bail and is covered or uncovered as the bail assumes various positions on its pivot. With my improved pivoted bail, not only is 90 a more efficient and stronger mechanical structure provided, but also one in which the design is ~~more~~ graceful and pleasing to the eye, which, as has been mentioned, is quite important in an article of this character. The outstanding feature of the improved design is that the sides of the bail are formed along upwardly converging lines, instead of having ~~more~~ or less vertical sides and a flat top.

I use in my improved construction, a rather short, broad and sturdy bail post, which fulfills two important functions. It carries the pivotal axis or pivot pin of the bail and provides a firm and reliable support for this axis; it also makes possible the use of a heavy strong pivot pin for the bail. Inasmuch as the whole weight of the

bag is carried on this pivot pin, it should be made unusually strong and absolutely reliable.

In addition to the features just described, 5 the bail post is provided with a catch or socket with which a latch member from the other side of the bag engages to hold the bag closed.

The improved construction of my bail 10 mounting will now be described in detail, after which a number of other advantages will be more readily apparent and will be pointed out below.

Referring to the drawing which represents 15 a preferred embodiment of my invention,

Figure 1 is a side view of a hand bag of usual form, provided with my improved bail mounting;

20 Fig. 2 is an enlarged side view of the mounting; and

Fig. 3 is a sectional-view of the same taken on the line 3—3 of Fig. 2.

In the drawing, the fabric or mesh of the 25 bag is indicated at 1, which is joined by the well known fastening spiral wire 2, to a pair of substantially U-shaped metallic frame elements 3 and 4, hinged together as is usual at 5. The frame elements 3 and 4 30 are substantially flat and fit together to form a closure for the bag.

One of the frame elements, such as 3, is provided with a bail post 6 which is rigidly attached to it. The bail post may be either 35 integral with the frame element 3 or it may be soldered or brazed on. This post is preferably of heavy and sturdy construction, for reasons that will be apparent below.

The bail post 6 has symmetrical laterally 40 extending portions 7 and an upper portion 8 which is provided with a groove 9. In order to provide a passage for a pivot pin, the bail post has drilled in it, through the laterally extending portions 7, a hole 10, 45 in which hole is positioned the pivot pin 11. The bail indicated at 12, is provided with a pair of relatively wide bearings 13, that engage with the pivot pin 11 to form a swiveled mounting for the bail. The 50 parts are shaped and finished so that a neat and pleasing appearance is presented. The bail 12 is, for the purpose of pleasing the eye, preferably made of the shape shown in Figs. 1 and 2, that is, with the two sides 55 of the bail converging upwardly, although, of course, it may be made in other shapes.

Attach d to the upper part of the bail is a sheet metal socket element 14, which is rigidly fastened thereto. In this socket 14 60 is mounted in any desired manner, a flexible handle 15 which may be of woven wire or other suitable material.

The other frame element 4 is provided with a fastening device of a well known 65 construction and comprises the spring arm

16 which is rigidly attached at its lower end to the frame 4 and which is provided with a more or less horizontally extending portion 17 which is provided with the ball or fastening pin 18, and, if desired, an ornamental stone 19. The parts just described are so designed that when the bag is closed the ball 18 snaps into the groove 9 and is held there by the resiliency of the parts 16 and 17 as is well known. The parts 75 are also preferably so designed that the bail swings over and just clears parts 16, 17 and 18 as shown in the dotted line positions A, B and C, Fig. 3.

It is an important feature of the invention 80 that the pivot pin 11 is below the fastening element, so that the pivoting of the bail takes place about an axis which is below the point of engagement of the ball 18 and its groove. With such a construction, 85 it is apparent that the bail 12, socket 14 and handle 15 may swing around in an arc of at least 180° about the pivot pin 11, some of the possible positions being shown in full and dotted lines in Fig. 3.

90 Further advantages of this construction will now be more fully described.

In the first place, with a construction in which the bail is rigid with the frame, an accidental blow against the ball 18 would 95 tend to unlatch the bag. With my improved construction, however, an accidental blow against the ball 18 would simply tend to make the bag swing with respect to its handle so that the handle would assume the position as shown in the dotted line position A, Fig. 3, and there would be much less likelihood of accidental unfastening on this account.

100 While then, the bag is not so readily unlatched accidentally, it may, under certain conditions, be very readily unlatched with one hand, whereas previous constructions in which the bail is rigid are only unlatched with one hand with considerable difficulty. 105 This feature is of practical value where the person who wants to open the bag has her other hand full of parcels. In order to open the bag using only one hand, the user holds the handle in the position shown in dotted lines B, Fig. 3, the handle 15 being horizontal and in the palm of the hand, with the index finger below the handle and against the bail post 6, whereupon the thumb may be engaged against the ball 18. In such a 110 position, the ball 18 will be uncovered and the portion 3 of the frame will be held rigidly by virtue of the handle B being in the user's hand. If now the thumb is pressed against the ball 18, the bag is readily unlatched.

115 Another advantage of my improved construction is that if it is desired to make the bag doubly safe against opening, the bail may be swung around to the position shown 120

in the dotted position C, Fig. 3 and held there, so that the bail 12 swings over the parts 16 and 17 of the latching arm, in which position, it will be apparent that even if the ball 18 should become disengaged from its groove, the bag could open only a very small amount so that nothing would be lost.

It is desired to call particular attention to the mounting of the pivotal axis on which the bail is pivoted or swiveled. The flared parts 7 of the bail post provide a wide, strong mounting for the pivot pin 11; both the bail post and the portions 7 are of heavy and thick metal and so permit the use of a comparatively long and heavy pivot pin 11. The whole weight of the bag, and also the strains to which it is subjected, are transmitted through the pivot pin. It accordingly should be made as proof against breakage as possible.

It is also desired to point out the location of the pivotal axis with relation to the ball catch 18. This axis is below the catch, a feature that permits the swiveling of the bail directly to the bail post, that dispenses with pivoting the handle carrying socket to the top of the bail, and that allows the bail to swing over the catch to cover or uncover it at will.

The particular form of pivot or swivel mount for the bail may, of course, be varied. For instance, the pivot may be made integral with the bail post, or the pivot pin might be made in two parts. These are obvious mechanical equivalents.

While the invention has been described in considerable detail, it should be understood that it is capable of expression in many other possible forms.

I claim:

1. In a hand bag, the combination of a pair of frame members, a bail post carried by one of the frame members, a pivot pin

carried by the bail post, a bail pivoted on the pivot pin, a flexible handle attached to the bail and a fastening device carried by the other frame member and engageable with the bail post above the said pivot pin.

2. In a hand bag, the combination of a pair of frame members, a bail post carried by one of the frame members, a pivot pin carried by the bail post, a bail pivoted on the pivot pin, a socket element fixed to the bail, a flexible handle mounted in the socket element and a fastening device carried by the other frame member and engageable with the bail post at a point above the location of the said pivot pin.

3. In a hand bag, a pair of frame members, a bail post mounted on one of the frame members, a latching device mounted on the other frame member, and a bail pivoted to the bail post, the latching device engaging the bail above the pivotal axis on which the bail post is mounted.

4. In a hand bag, the combination of a pair of frame members, a bail post carried by one of the frame members, a bail pivoted to the bail post, a socket element fixed to the bail, a flexible handle mounted in the socket element and a fastening device carried by the other frame member and engaging with the bail post above the pivotal connection of the bail with the bail post.

5. In a hand bag, a pair of frame members, a bail post carried by one of the frame members, a bail pivoted to the bail post, a latch carried by the other frame member and engageable with the bail post above the pivotal connection between the bail and the bail post, the bail being swingable through an arc of about 180° so as to either clear the latch entirely or to straddle the latch and prevent the opening of the bag.

In testimony whereof I affix my signature.

HARRY BRADLEY ROWAN.
